UNITED STATES PATENT OFFICE.

BALTHASAR E. REUTER, OF CHICAGO, ILLINOIS, ASSIGNOR TO REUTER PROCESS COMPANY, OF CHICAGO, ILLINOIS, A CORPORATION OF ILLINOIS.

APPARATUS FOR THE DECOMPOSITION OF FATS AND OILS.

1,227,198.

Specification of Letters Patent.

Patented May 22, 1917.

Application filed November 7, 1913. Serial No. 799,699.

To all whom it may concern:

Be it known that I, BALTHASAR E. REUTER, a citizen of the United States, residing at Chicago, in the county of Cook and 5 State of Illinois, have invented a certain new and useful Improvement in Apparatus for the Decomposition of Fats and Oils, of which the following is a full, clear, concise, and exact description, reference being had 10 to the accompanying drawings, forming a part of this specification.

My invention relates to apparatus for use in the treatment of fats or oils, the object of my invention being to provide improved 15 equipment whereby the fats or oils may be decomposed, the glycerin content removed therefrom, and the said fats or oils rendered free from discoloration. The apparatus hereinafter described is particularly intended 20 ed for use in carrying out the processes disclosed in my Patent No. 1,068,079, issued July 22, 1913, and my co-pending applications Serial Nos. 698,615 and 730,214, filed respectively on May 2, 1912 and November 25 8, 1912.

Generally my invention consists in a plurality of tanks for carrying out the above-mentioned process and mechanism associated with or connecting said tanks, the operation of which is described in the following specification, reference being made to the accompanying drawings, in which—

Figure 1 represents the apparatus of my invention, all of said apparatus with the exception of the saponification tank being illustrated more or less diagrammatically; and

Fig. 2 is a fragmentary detail view of the air-tight closure for the opening in the 40 top of the saponification tank.

In the drawings A indicates the acid treating or wash tank; B is a tank for the storage of wash water recovered from A; C is the saponification tank; D indicates the 45 sweet water or glycerin storage tank; E represents the tank for storing and bleaching the fatty acids recovered from the saponification tank C; F represents the condensed or distilled water tank.

The acid treating or wash tank A is open 50 at the top, as shown, and is preferably provided with a lead lining in order that it may not be affected by the acid with which a charge admitted to the said tank is treat-

ed. The wash tank is also preferably pro-

vided with a mechanical agitator 3 and a steam coil 4 having jets 5, said coil being connected with a steam supply pipe as shown. The mechanical agitator with which the acid treating plant is equipped is conveniently, in all respects, similar to the agitator with which the saponification and bleaching tanks are provided and therefore a description of the agitator of the saponification tank will suffice for all. 60

The storage tank B requires no detail description. It will suffice to say that this tank is connected with the wash tank A by suitable piping 7.

The saponification tank C is air-tight and 70 comprises the outer tank or shell 8 having a lead lining 9, which of course is not affected by the sulfuric acid which is employed in carrying out the process of decomposing the fats or oils. The bottom of the saponification tank slopes toward the center as shown. The said tank is provided with a steam coil 10 having jets 11, said steam coil being connected by a pipe 12 with a steam supply pipe 65 6. Said saponification tank is also provided with a mechanical agitator which comprises two marine propellers which are rotated in opposite directions. Supported by the bottom of the saponification tank is a bracket 13 in which bears the lower end of a shaft 14, 80 which has mounted thereon the propeller 15. Said shaft passes through the top of the saponification tank and terminates in a gear case 16, where it is provided with a bevel gear 17. The gear case 16 is supported by a platform 18 as shown. Disposed around the shaft 14 is a quill shaft 19 which has a propeller 15 mounted upon its lower end, the upper end thereof terminating in gear case 16, where it is provided with a bevel gear 95 20. Disposed at right angles to shafts 14 and 19 is a shaft 21 which projects into gear case 16 and has attached thereto a bevel gear 22 meshing with bevel gears 17 and 20. It is evident when the pulley 23 attached to the shaft 21 is driven from any suitable source of power, the shafts 14 and 19 and consequently the propellers 15 and 13 will be rotated in opposite directions. In the operation of the agitator the propellers moving in 100 opposite directions serve effectually to break the treated materials into very small particles and so facilitate the decomposition thereof.

The saponification tank is also equipped 110

with a plurality of stop-cocks 24 and a pressure gage 25 as shown. The opening 26 in the top of the saponification tank is closed by means of a cover 27 as is clearly shown in Fig. 2. The tank carries an annular cover support 28 having a groove 29 into which an annular lip 30 carried by the cover 27 is arranged to project. A quantity of water or other suitable liquid is poured into the groove 29 in order to form an air-tight seal between the cover 27 and its support 28. As the cover 27 is usually quite heavy, I prefer to attach thereto a rope or cable 31, which passes over a pulley 32 and is provided with a counterweight 33.

As is pointed out in my patent above referred to, it is desirable to prevent air from coming into contact with the contents of the saponification tank. It is evident from the drawing that the steam which collects in the saponification tank above the contents therein effectually excludes air from said tank.

The sweet water tank D is connected by pipes 34 and 35 with the pump 36 and the saponification tank C, respectively.

The bleaching and storage tank E is provided with a mechanical agitator 37 and a steam heating coil 38 connected by means of a pipe 39 with the live steam pipe 6, said coil being also connected with the pipe 40 leading to any suitable point. The bleaching tank E is also provided with a heating coil 41, one end of which is connected with a pipe 42 terminating in the saponification tank, the other end of said coil being connected to a pipe 42^a terminating in an overflow cup 43 in the tank F. The pipe 44 has one end in the tank E and the other end in an overflow cup 45 also in the tank F. By providing the overflow cups 43 and 45 and the associated apparatus just described, I am enabled to maintain atmospheric pressure within the saponification and bleaching tanks, at the same time preventing temperatures over 212° Fahr. As is clearly pointed out in patent and patent applications referred to, it is very necessary, in order that my processes be satisfactorily car-

ried out, to maintain pressures not substantially above atmospheric pressure and to maintain temperatures not substantially over 212° Fahr.

At 46 I have illustrated an acid storage tank mounted for convenience upon scales 47. The contents of this acid storage tank 55 may be connected through suitable piping to the acid treating, saponification and bleaching tanks. I have not attempted to mention all of the valves in detail, as their functions will be apparent at once from an inspection of the drawing. The agitator with which the acid treating tank is equipped may be dispensed with if desired.

While I have illustrated my invention in the particular embodiments herein shown and described, I do not wish to limit myself to these particular constructions, but desire to claim broadly any equivalents thereof which may suggest themselves to those skilled in the art to which my invention relates.

I claim as new and desire to secure by Letters Patent:

As a means for decomposing fats or oils, the combination of an open tank having a, 75 steam jet coil for heating the contents thereof, a closed tank having a steam jet coil and provided with a mechanical agitator, said tank receiving fats or oils previously heated in said first tank, a third tank for receiving glycerin water from the second tank, a closed bleaching tank provided with a closed heating coil and a mechanical agitator for receiving the decomposed fatty acids from the second tank, and means for 80 filling the top of the last-named tank with steam at substantially atmospheric pressure to prevent access of air to the contents of the tank.

In witness whereof, I hereunto subscribe 90 my name this 4th day of November, A. D. 1913.

BALTHASAR E. REUTER.
